UNITED STATES PATENT OFFICE.

WILLIAM LORAN FODREA, OF LITTLE ROCK, ARKANSAS.

WIREWORKING MACHINE.

Application filed November 3, 1922. Serial No. 598,785.

To all whom it may concern:

Be it known that I, WILLIAM L. FODREA, a citizen of the United States, residing at Little Rock, in the county of Pulaski and State of Arkansas, have invented certain new and useful Improvements in Wireworking Machines, of which the following is a specification.

This invention relates to wire working machines, and more particularly to machines for making wire fabric.

An object of the invention is the provision of a machine for twisting two or more pieces of wire to form wire fabric.

15 In the form of the invention disclosed, I provide a pair of gears, one of which is mutilated and provided with means for grasping the wires, and means for intermittently rotating said gears to twist two 20 pieces of wire held by said mutilated gear.

I further provide a guide through which the wires are adapted to pass, means for lowering said gears to permit the mutilated gear to grasp the wires, and means for rotating said gears while lowered.

In the accompanying drawings, I have shown one embodiment of the invention. In this showing:

Figure 1 is a front elevation of the machine,

Figure 2 is a side elevation of a casing in which the gears are mounted,

Figure 3 is vertical longitudinal sectional view through the casing, showing the gears in one position,

Figure 4 is a similar view showing the gears in a second position,

Figure 5 is a horizontal sectional view on line 5—5 of Figure 3,

40 Figure 6 is a similar view on line 6—6 of Figure 3,

Figure 7 is a detail view of a cam for raising and lowering the gears,

Figure 8 is a diagrammatic view showing 45 a plurality of the machines employed in the construction of wire fabric,

Figure 9 is a view of a finished piece of fabric.

Figure 10 is a perspective view of a wire fence showing the manner in which the fence posts are inserted, and

Figure 11 is a detail sectional view on line 11—11 of Figure 1.

50 Referring to the drawings, the reference numeral 1 designates a standard having a pair of bearings 2, adapted to receive a shaft

3. The shaft is provided with a collar 4 and a coil spring 5 is arranged between this collar and the lower bearing to normally retain the shaft in raised position. A plate 6 is secured to the bottom of the shaft and a casing 7 is secured to this plate. As shown, the casing is provided with side walls 8 and front and rear walls 9, the bottom of the casing being open. The bottom of 65 the side walls of the casing are provided with inclined cut-away portions 10, forming a guide for the wire to be twisted.

A gear 11 is mounted on a shaft 12, arranged in the upper part of the casing, and this shaft projects through the walls of the casing (see Figure 1). A lower gear 13 is arranged in the casing and is adapted to mesh with the gear 11. As shown, the lower gear is provided with a mutilated or cut-out portion 14. A pin 15 is arranged centrally of the cut-out portion 14, and the outer end of the pin is arranged in the arc described by the gear forming a tooth.

Suitable guide means for the wire are 80 arranged below the normal position of the casing. As shown, a pair of upper bars 16 are arranged on opposite sides of the casing, and similar bars 17 are arranged beneath these bars and slightly spaced therefrom. 85 Wire strands 18 are delivered through the space between the bars.

The casing is adapted to be lowered by means of a cam 19, mounted on a shaft 20. The shaft 20 is mounted in a bearing 21 in the frame of the machine and is driven in any suitable manner. As shown, the low portion 22 of the cam is flat throughout a considerable distance, so that the casing will be retained in lowered position for a relatively long period of time. The shaft 3 is provided with a roller 23 on its upper end, adapted to engage the cam. The gears are adapted to be rotated when in lowered position to twist the wire after it has been engaged by the pin 15. A gear wheel 24 is mounted on shaft 20. This gear is provided with teeth 25, extending throughout a portion of its periphery, and is provided with a smooth portion 26. A pinion 27 is adapted to mesh with this gear. This pinion is provided with teeth 28, and is further provided with an interrupted portion 29. As shown, the portion 29 is arranged on an arc parallel to the surface 26 of the gear 24. The pinion is mounted on a shaft 33. The shaft 30 is received in a bearing 34 and is provided

100

105

110

with collars 35, arranged above and below the bearing. A sleeve 36 is mounted on this shaft and revolves therewith, the sleeve being capable of longitudinal movement on the shaft and being secured thereto by a key 37. The upper gear shaft 12 is provided with a bevel gear 38, adapted to mesh with a bevel gear 39, carried by the sleeve. As shown, the sleeve is received in a bearing 40, carried by the plate 6, and a collar 41 is arranged on the sleeve above this plate. The bevel gear 39 is provided with a hub 42 which contacts with the lower face of the bearing.

15 In Figure 8 of the drawings, I have diagrammatically shown a number of the machines used for the purpose of constructing a relatively large piece of wire fabric. As shown, the wires 18 are formed in pairs and 20 are delivered to a plurality of machines A arranged in a transverse row. The wires passing through the machines A are twisted and the adjacent wires of each pair are then brought together as indicated by the sections or strands 43. These strands are then 25 passed through a second battery of machines B, arranged in staggered relation to the machines A and after being twisted, the wires are fed through the machines a distance equal to the major axis of the diamond 30 sections formed. If desired, the loops 44 may be preformed in the wires to indicate proper distance the wire is to be fed each time.

35 In Figure 9 of the drawings, I have shown a finished sheet of fabric consisting of straight end wires 45, and diagonal wires 46. Where the wires intersect, they are provided with twisted portions 47 having 40 loops 48 arranged centrally thereof. These loops are formed by the portion of the wire surrounding the pin, as shown in Figures 3 and 4 of the drawings. When the wire is delivered from the machine, the loops are 45 arranged in the plane of the fabric. If the wire is to be employed as fence wire, the loops may be twisted to a position at right angles to the plane of the fabric, as indicated at 49 in Figure 10 of the drawings, and a suitable post 50 passed through the 50 alined loops.

The operation of the device will be apparent from the foregoing description. The machine is driven through shaft 20. The 55 gear casing is normally retained in raised position by the spring 5 and upon each revolution of the shaft 20, the low portion 22 of the cam engages roller 23 and forces the gear casing downwardly against the tension of the spring. As the gear casing lowers, the wire strands 18 engage the inclined walls 10 at the bottom of the gear casing and are fed upwardly to a position on opposite sides of the pin 15. During this portion of the operation, the pin is in the po-

sition shown in Figure 3 of the drawings. Due to the relatively large flat surface 22 formed on the cam, the casing is retained in lowered position for a considerable period of time. While the casing is in lowered position, the teeth 25 of the gear 24 engage the teeth 28 of pinion 27 to rotate the shaft 33, and thus rotate gears 11 and 13. As the gears are rotated, the end of the pin 15 serves as a tooth, as shown in Figure 4 of the drawings, and a complete revolution of the gears takes place while the teeth 25 and 28 are in mesh. This forms the twist 47 shown in Figure 9 of the drawings. When the low portion 22 of the cam is about to 80 disengage the roller 23, the gears have completed a revolution and are again in the position shown in Figure 3 of the drawings. This permits the wire to pass off the end of the pin as the casing is moved upwardly within the guides 16 and 17 and the wires may then be fed through the guides the desired distance before another twist is formed.

The gears 38 and 39 are kept in mesh at 85 all times by providing the sleeve 36, slidably mounted on the shaft 33. This sleeve is supported in the bearing 40, which is carried by the plate 6 and thus raises and lowers with the gear casing. The collar 41, contacting with the upper end of the bearing, causes the gears to move upwardly in mesh and the hub 42 of gear 39 engaging the lower face of the bearing keeps them in mesh when moving downwardly.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention. I claim:

1. In a device of the character described, a guide for receiving strands of wire; a twisting member normally disposed above said guide, means for reciprocating said twisting member through said guide, and means for actuating said twisting member when it is within said guide to twist strands of wire.

2. In a device of the character described, a guide for receiving strands of wire, a pair of gears normally disposed above said guide, one of said gears being provided with means for receiving said wires and twisting them when the gears are rotated, means for reciprocating said gears through said guide, and means for rotating said gears when they are in lowered position.

3. In a device of the character described, a guide adapted to receive strands of wire, a pair of gears disposed adjacent said

guide, one of said gears being provided with a projecting pin adapted to engage said strands of wire and twist them when the gears are rotated, means for reciprocating said gears through said guide, and means for rotating said gears.

4. In a device of the character described, a guide for receiving strands of wire, a pair of gears, means for reciprocating said 10 gears through said guide, one of said gears being mutilated and provided with a pin in said mutilated portion, said pin being adapted to engage said strands of wire when the gears are passed through said 15 guide, and means for rotating said gears to twist the strands of wire engaged by said pin.

5. In a device of the character described, a guide, a pair of gears disposed adjacent 20 said guide, a cam adapted to reciprocate said gears through said guide, one of said gears being mutilated, a pin arranged in the mutilated portion of said gear to engage said strands of wire when the gear passes 25 through said guide, and means for rotating said gears to twist said strands of wire.

6. In a device of the character described, a main shaft, a cam mounted on said shaft, a reciprocating member engaging said cam, 30 a pair of gears carried by said reciprocating member, one of said gears being provided with means for engaging strands of wire, a guide disposed adjacent said gears and adapted to receive strands of wire to be 35 engaged by said means when said gears are reciprocated, gearing connecting said gears to said main shaft to rotate them, and means for retaining said gearing in mesh during the reciprocation of said reciprocating member.

7. In a device of the character described, a main shaft, a cam mounted on said main shaft, a reciprocating member engaging said cam, a pair of gears carried by said 45 reciprocating member, one of said gears being mutilated and provided with a pin arranged in said mutilated portion and

adapted to form a tooth, said pin being adapted to engage strands of wire to twist them when the mutilated gear is rotated, 50 a guide disposed adjacent said gears, said mutilated gear being adapted to pass through said guide to permit said pin to engage strands of wire arranged in said guide, and means for intermittently rotating said gears, said means including a pair of segmental gears, one of said gears being mounted on said main shaft, the other gear being mounted on an auxiliary shaft, and connections between said auxiliary shaft 55 and said first pair of gears.

8. In a device of the character described, a main shaft, a cam mounted on said shaft, a reciprocating member engaging said cam, 60 a casing carried by said member, a pair of gears mounted in said casing, one of said gears being mutilated and being provided with a pin arranged in the mutilated portion, said pin being adapted to engage strands of wire to twist them, a guide disposed adjacent said casing and adapted to receive strands of wire to be twisted, 65 one of the gears in said casing being provided with a shaft projecting beyond said casing, a counter-shaft connected to said main shaft to intermittently rotate it, a sleeve slidably mounted on said counter-shaft and adapted to rotate therewith, a gear carried by said sleeve, and a gear mounted on said projecting shaft and meshing 70 75 80 85 therewith.

9. A device constructed in accordance with claim 9, wherein the means for intermittently rotating said counter-shaft comprises a pair of segmental gears, one of 85 said gears being arranged on said main shaft, and the other on said counter-shaft.

In testimony whereof, I affix my signature in presence of two witnesses.
